UNITED STATES PATENT OFFICE.

CHARLES GOLDSTEIN, OF CHICAGO, ILLINOIS.

BOOKBINDER.

Application filed May 1, 1924. Serial No. 710,355.

To all whom it may concern:

Be it known that I, CHARLES GOLDSTEIN, a citizen of the United States of America, and a resident of Chicago, county of Cook, and State of Illinois, have invented a certain new and useful Improvement in Bookbinders, of which the following is a specification.

This invention relates to improvements in book binders and more particularly to binders in which the contents are separable from the cover, thus permitting the former to be renewed as required.

Among the objects of the invention is to provide a novel construction for binders of the general character described and more especially suitable for use in the manufacture of check books, memorandum or note books, and the like, wherein the fillers or contents consisting of bound together sheets, are supplied from time to time as used.

A further object of the invention is to provide a simple and inexpensive form of mounting for the filler and cover, which can be supplied to the book maker independently of the cover and filler stock, thus permitting the maker to assemble and put on the market the complete binders and fillers without the use of special assembling equipment.

A preferred embodiment of the invention is illustrated in the accompanying drawings in which,

Figure 1 is a perspective view of the filler showing the application of the binding strip.

Figure 2 is a view in cross section of the filler as taken on line 2—2 of Figure 1.

Figure 3 is a plan view of the cover in open position and lying flat.

Figure 4, is a cross sectional view through the back section of the cover as taken on line 4—4 of Figure 3.

Figure 5 is a view in longitudinal section taken on line 5—5 of Figure 3, and,

Figure 6, is a cross sectional view of the filler and cover assembled.

The cover of the binder is made in any of the various forms known in the binder art, consisting of the cover members 1, 1, and the back section 2, the covers being either stiff or limp, and of any suitable material. The back section 2, is preferably stiff, and connected along its sides with the covers by limp hinging sections 3, 3.

Extending substantially the full length and width of the back section, is a channel

strip 4, made of a light gauge metal and having its edges bent over and toward each other to form marginal channel members 4^a, 4^a opening inwardly and toward each other. 60 The channel strip is manifestly mounted on the inside face of the back section, this being accomplished by passing rivets 5 through the channel strip and back sections at several points throughout the length. At one end 65 of the channel strip it is provided with an upstanding lip or stop member 6, which is bent up from the material of the strip and forms a closure for one end of the channel to prevent the endwise movement of the 70 filler in one direction. At the other end the channel is open and a spring locking member 7, is provided, the same consisting of a narrow strip of metal lying underneath the channel strip and having its inner end anchored 75 by one of the rivets 5. The end of the locking member projects beyond the end of the channel and is bent to form an upstanding detent 7^a adjacent the end of the channel strip and a rounded extremity 7^b, whereby the 80 pressure of the thumb or finger may be applied to press the detent below the end opening to the channel strip. The binding strip 8, which serves as the connecting member between the filler and the channel strip 85 4, is applied along the back edge of the bound sheets 9, the two together forming the completed filler. In practice the bound sheets, which may be blank checks or the like, would ordinarily be bound together by 90 sewing or stapling prior to the application of the binding strip. The strip consists of a strip 10, of fabric such as cambric, having its inner surface gummed. Sewed to the fabric strip 10, is a narrow strip 11, of a 95 relatively stiff material such as a fibre or press board of a width and thickness approximating that of the channel formed by the channel strip 4. As a preferable method of securing the strip 11 to the fabric to lines 100 of holes 11^a are punched in the latter, there extending lengthwise on either side of the central line and through these holes are sewed the lines of stitching 12, 12. The binding strip 8 is thus a unitary piece which 105 is readily applied to the back of the bound sheets 9, by moistening the gummed surface and folding its margins over the sides with the strip arranged symmetrically along the back. The binding strip thus applied provides a relatively flexibly connected member along the back of the filler which can 110

be inserted or slid endwise into the channel strip, with its margins engaging within the U-shaped channels. The spring locking member 7, is pressed downwardly and out of locking position during the insertion of the filler and when in position, the locking member resumes its position with the detent 7^a preventing the same from sliding out.

The filler thus inserted is not directly secured to the cover, but through the medium of the channel engaging strip 11, which has flexible connection with the filler. Thus there is no binding between filler and cover such as would make the binder less flexible than a permanently bound book. This is particularly true of a sectionally sewed filler, since the application of the binding strip does not effect its flexibility in the sense that it can be opened flat.

A further advantage has already been mentioned namely, that the channel and binding strips are so constructed that they can be applied to cover and filler without expert labor and special equipment. This makes it possible for the book maker to buy the manufactured material on the market in large quantities, and cut it to the length required. This is especially true of the binding strips which can be applied to fillers of most any form and varying thickness, and used with any form of cover provided with

channels or grooves to receive the edges of the stiff strip.

I claim as my invention:

1. A binder comprising separable cover and filler therefor, and connecting members comprising a channel strip applied to the cover and a binder strip consisting of a relatively stiff strip adapted to be inserted in said channel strip and stitched to a piece of flexible material adapted to be applied along the back edge of said filler.

2. A binder comprising separable cover and a filler therefor, and intermediate connecting members comprising laterally opening channels along the back section of said cover and a binder strip on said filler comprising a fabric strip applied along the back of said filler and a strip of relatively stiff material flexibly connected with said fabric strip by a line of stitches extending lengthwise intermediate its side edges.

3. A binder comprising a separable cover and filler, a channel along the back section of said cover, a flexible strip applied along the back edge of said filler, a relatively stiff strip flexibly connected with said flexible strip and means for locking said parts in connected position.

Signed at Chicago, this 12th day of April, 1924.

CHARLES GOLDSTEIN.
